INVENTOR
Charles B. Waters
BY *Frank J. Schmitt*
ATTORNEY

UNITED STATES PATENT OFFICE.

CHARLES B. WATERS, OF MONTCLAIR, NEW JERSEY.

HEATER FOR MOTOR CARS.

Application filed December 24, 1924. Serial No. 757,797.

To all whom it may concern:

Be it known that I, CHARLES B. WATERS, a citizen of the United States, and a resident of Montclair, in the county of Essex and State of New Jersey, have invented certain new and useful Improvements in Heaters for Motor Cars, of which the following is a specification.

The invention relates to motor car heaters adapted for heating the interior of a motor car or self-propelled vehicle; and it has for its object means for accomplishing this in a simple and efficient manner to afford the proper degree of warmth and without the usually attendant objectionable odors. A further object of the invention consists in a heater which will continue to function for an appreciable time after the shutting down of the motor of the said vehicle. A still further object of the invention resides in a device of this character which will entail no appreciable loss of power and the use of which, as a matter of fact, is beneficial to the operation of the motor.

Further objects are a rugged and readily and quickly installed device, requiring but a minimum amount of labor for its installation.

The nature of the invention, however, will best be understood when described in connection with the accompanying drawings, in which—

Fig. 1 is a fragmentary elevation illustrating the motor and radiator of an internal combustion engine, a portion of the body of the self-propelled vehicle and the novel heating apparatus secured in position.

Fig. 2 is a detail longitudinal section of the fitting member employed; and Fig. 3 is a transverse section thereof taken on the line 3—3, Fig. 2, looking in the direction of the arrows.

Referring to the drawings, 10 designates an internal combustion engine of any well-known or special type and having associated therewith the usual water cooling system including a radiator 11 and a pipe connection 12 between said radiator and the water jacket of the internal combustion engine.

In accordance with the invention, the cooling system is opened, as at the connection 12 between the water jacket of the engine 10 and the radiator 11, for the insertion of a suitable fitting 13 which is shown in detail in Figs. 2 and 3. This fitting consists

essentially of a short length of piping to the ends of which are adapted to be connected the corresponding ends of the said connection 12 between radiator and internal combustion engine and which is generally in the form of a flexible hose member. As is the usual practice, the connection 12 is inclined from the engine 10 to the radiator 11 with its lowermost end at the engine portion, and the fitting 13 assumes substantially the same angle of inclination. Moreover, in accordance with the usual practice, the cooling water is circulated between the radiator and engine as by means of a pump 14, and passes upwardly thru the connection 12 and thus also thru the inserted fitting 13. Preferably, along the lower or under surface of this fitting, taps are provided as at 15 and 16, the former being at a lower level than the latter and each being provided with inwardly projecting fins or blades 17 and 18, respectively. The former blade 17 is bent downwardly and in a direction to oppose the incoming stream of water while the blade 18 is also bent downwardly but in the reverse direction with reference to the fitting, that is to say, in the direction of flow thru said fitting and reduces somewhat the aperture.

From the taps 15 and 16 thus provided, connection is made, as by means of corresponding hoses or pipes 19 and 20, to a radiating member 21 which may be placed at any convenient location along the floor of the car to suit requirements. Any suitable form of radiating member which will permit of circulation of water therethru may be employed; and there is inserted in the incoming line 19, a valve 22 for controlling the supply. This valve will be located conveniently for control by the operator of the car so that the heat afforded by the radiating member 21 may be varied as desired.

In operation, a portion of the heated water passing thru the fitting 13 will be diverted by the fin or blade 17 thru the tap 15 and hose 19 to set up a circulation, when valve 22 is open, thru the heat radiating member 21 and back thru the hose 20 to the tap 16. It will be noted that the fin or blade 18 forms a more or less constricted aperture at the tap 16 which, in conjunction with the velocity of the stream passing upwardly thru the fitting 13 and past the said

aperture, will tend to provide an ejector action to further induce circulation thru the connections 19—20.

By the expedient hereinbefore described, 5 a circulation of comparatively hot water may be maintained to provide the desired degree of warmth in the car; and it will be appreciated that, as water retains its heat for a considerable period, the stopping of 10 the engine will not immediately shut off the supply of heat as is the case with heating devices receiving their supply of heat from the exhaust of the engine. Moreover, there is no danger of objectionable odors from the 15 exhaust entering the car thru the use of the novel heating device, and there is no loss of power involved in its use. As a matter of fact, additional radiating surface is thus provided to assist in the cooling of the 20 circulating liquid which in some motors has a tendency to become overheated. The installation of the fitting, furthermore, is an extremely simple matter as it is necessary merely to replace the usual hose connection 25 12 between engine and radiator by a connection including the said fitting and then make the necessary connections to the radiating member 21.

I claim:—

30 1. In combination with a water cooling system, a hot water heating system comprising means for diverting part of the water from said cooling system under a circulating pressure built up by the velocity of flow 35 of the water in said cooling system; a radiating member disposed below said diverting means; a feed conduit connecting said diverting means with said radiating member; means disposed above said radiating member 40 and adjacent said diverting means for

returning the diverted portion of water to said cooling system; and a return conduit connecting said last mentioned means with said radiating member.

2. In combination with a water cooling 45 system for an engine, an outlet opening for diverting part of the heated water from the cooling system at a point above the engine; a deflecting lip over said outlet opening; a radiating member disposed substantially below said outlet opening; a conduit connecting said outlet opening with said radiating member; a return opening for the diverted water at a point above said outlet opening 50 in said cooling system; a deflecting lip over said return opening; and a conduit connecting said radiating member with said return opening.

3. In combination an internal combustion 55 engine, a water cooling system therefor comprising a cooling radiator and a force feed pump; means interposed between said engine and said cooling radiator for diverting a part of the circulating water from the cooling system under pressure built up by the velocity of flow of the water in the cooling system; means interposed between said diverting means and said cooling radiator for increasing the suction produced by the 60 velocity of flow in the cooling system on the diverted water; and a radiating member through which the diverted water is circulated disposed below the level of and connected to said first and said second mentioned means.

Signed at New York, in the county of New York and State of New York, this 23rd day of December A. D. 1924.

CHARLES B. WATERS.
